UNITED STATES PATENT OFFICE.

GEORGE B. BOSCO, OF CHICAGO, ILLINOIS.

FORM CLAMP.

Application filed February 5, 1923. Serial No. 617,039.

To all whom it may concern:

Be it known that I, GEORGE B. Bosco, a citizen of the United States of America, and a resident of Chicago, county of Cook, and 5 State of Illinois, have invented a new and useful Improvement in Form Clamps, of which the following is a specification.

This invention relates to clamps and in its principal embodiment is applied to form 10 clamps for holding together the separable parts of a concrete mold.

The main objects of this invention are to provide improved means for readily drawing together the separable parts of a mold; 15 to provide an improved construction and arrangement of means for holding the parts of the mold together while the concrete is being poured and is setting; to provide holding means of the above character which 20 are readily detachable from the mold so as to permit the latter to be stripped after the concrete has set; and to provide a form clamp of this kind which eliminates the use of screw threads and which is inexpensive 25 to manufacture and simple and effective in operation.

Illustrative embodiments of this invention are shown in the accompanying drawings, wherein:—

30 Figure 1 is a plan view of a column mold having one form of form clamp applied thereto.

Figure 2 is a transverse section of a girder mold having applied thereto another form 35 of clamp.

Figure 3 is a plan view of a wall mold having applied thereto the form of clamp shown in Figure 2.

Figure 4 is an enlarged perspective view 40 of a detachable tool used in tightening the clamp.

Figure 5 is an enlarged detail of the clip applied to the I-beam also in Figure 2.

Figure 6 is an enlarged perspective view 45 of the holding member or collar shown in Figure 1.

Figure 7 is a plan view of the same.

Figure 8 is a longitudinal section of the same, showing also a part of the tie band 50 and detachable tool.

Figure 9 is a side elevation of the wedge used in connection with the collar shown in Figures 6, 7 and 8.

Figure 10 is an enlarged perspective view 55 of the collar used on the clamps shown in Figures 2 and 3.

Figure 11 is a plan view of the same.

Figure 12 is a longitudinal section of the same, showing also a part of the tie band and detachable tool. 60

Figure 13 is a perspective view of a wedge used in connection with the collar shown in Figures 10, 11 and 12.

In the construction shown, the form clamps to which this invention is applied, involve the use of a tie element, and a holding member in the form of a collar mounted on the tie element for adjustment longitudinally thereof. Adjustment of the holding members on the tie element is accomplished 70 by means of a detachable tool adapted to grip the tie element at a point beyond the collar for pulling the former relative of the latter. Improved means are also provided for locking the collars to the tie elements 75 without the use of screw threads.

As illustrated, the form clamp comprises a tie element 1, a holding member or collar 2, and a tool 3 which is detachable so that one such tool may serve a large number of 80 clamps.

In the form shown, the tie element 1 is in the form of a flexible metal band, the size of which is dependent upon the character of the mold to which the clamp is applied. 85

Referring to the drawings, there are shown two types of holding members or collars 2. One type of collar for use with clamps applied to column molds is shown in Figures 1, 6, 7 and 8. Another type of collar for use with clamps applied to other forms of molds is shown in Figures 2, 3, 10, 11 and 12. 90

In the particular embodiment herein illustrated, the holding member or collar 2 comprises a block having a pair of intersecting slots 4 and 5 extending therethrough at substantially right angles to each other. The slot 4 is rectangular in cross section and is arranged to receive the tie band 1, which extends through the holding member. The slot 5 is formed to provide a key-way for a wedge which is adapted to coat with the tie band for clamping the latter to the collar. The wedge used in connection with the type 100 of collar illustrated in Figures 6, 7 and 8 is shown at 6 in Figure 9, and the wedge used in connection with the other type of collar herein illustrated is shown at 7 in Figure 13. The edges of the slot 5 are arranged 105 so that the edge of the wedge which engages the tie band 1 is always disposed in parallel

110

relation to the tie band while the wedge is being driven into its seat, thereby exerting a uniform pressure on the band. The slot 5 is greater in width than the thickness of the 5 slot 4 at the intersection between the two slots so as to form depressions 8 which will permit a buckling of the tie band under the action of the wedge, thereby affording a better grip on the band. Formed on the face of 10 the collar 2, is a seat 9 adapted to form a bearing for the tool 3 to permit the tool to be fulcrumed on the collar for pulling the tie band relative to the collar 6.

The type of holding member 2 shown in 15 Figures 1, 6, 7 and 8 is provided with an extension 10 having an opening 11 formed therein through which extends a transversely disposed pin 12, arranged to permit one end of the metal strap 1 to be laced 20 through the opening 11, as shown in Figure 8, for securing the strap against slipping by the friction of the overlapping parts.

The tool 3 comprises a shank 13 providing a handle, and an enlarged head 14 having its 25 end rounded so as to be adapted to be fulcrumed on the seat 9 of the collars 2. Extending through the head 14 is a pair of intersecting slots 15 and 16 disposed at substantially right angles to each other. 30 The slot 15 is arranged to receive the tie band 1, so as to permit the tool to grip the portion of the band projecting beyond the collar 2, for tightening the column. The slot 16 forms a key-way for the 35 wedge 7, and is formed so as to provide depressions 17 on opposite sides of the slot 15 to permit a buckling of the tie band under the action of the wedge.

In the embodiments shown in the drawings, the improved form clamps are applied 40 to three different kinds of concrete molds, viz: a column mold as shown in Figure 1, a girder mold as shown in Figure 2, and a wall mold as shown in Figure 3.

The column mold shown in Figure 1 comprises side sections which are formed of planks 18 secured together by battens 19 arranged on the outside of the mold and disposed transversely to the planks. In this 50 type of mold, the tie element 1 embraces the form and is held in place on the form by the single type of holding member or collar 2 illustrated in Figures 6, 7 and 8.

The girder mold shown in Figure 2 comprises the usual sections 20 and battens 21 surrounding the I-beam 22. In this type of mold, the tie bands 1 are arranged so as to become embedded in the concrete. The bottom girder section is supported by a plurality of clamps spaced apart at regular intervals along the beam, and in which the tie bands are bent around the I-beam in U-form. The ends of the tie bands project 60 through slots formed in the battens 21 of the bottom mold sections, and are clamped 65

to the collars 2. In the clamps which are applied to the side sections of the girder mold, the inner ends of the tie bands 1 are secured to the flange of the I-beam by means of U-shaped clips 23, as shown in Figures 2 and 5. Formed in the clip 23 is a slot 24 arranged to receive the end of the tie band, so as to permit the latter to be clamped between the clip and the flange of the beam, as shown in Figure 5. The outer ends of the tie bands in this construction project through the battens 21 of the side sections and are clamped thereto by the collars 2.

The wall mold shown in Figure 3 comprises the usual side sections 25, cross pieces 26, and battens 27. In the clamps applied to this type of mold, the tie bands 1 project through the mold so as to become embedded in the concrete, and the collars 2 abut against the outside of the mold.

In operation, the tie band is inserted through the slot 4 of the collar 2, so as to project beyond the seat 9. The tool 3 is placed on the seat 9 as shown in Figures 8 and 12, and the end of the tie band is inserted into the slot 15 of the tool. If the projecting part of the tie band is of sufficient length to permit the extremity thereof to be bent back upon the head 14 of the tool, as shown in Figures 3 and 8, it is not necessary to insert the wedge 7 into the key-way 16 in order to get a proper grip on the tie band. If the projecting part of the tie band is not of sufficient length to permit it to project through the slot 15, then a wedge may be employed as shown in Figure 12. In tightening the clamps having the type of collar 2 shown in Figures 1 and 8, the tool 3 is rocked in the direction of the arrow 28, and with the other type of collar the tool is rocked in the direction of the arrow 29. When the tie band 1 has been adjusted to the proper position relative to the collar 2, the wedge is inserted into the key-way 5 so as to clamp the collar to the band. The tool may then be removed for use on other clamps.

Although but certain specific embodiments have been herein shown and described, it will be understood that numerous details of the constructions shown may be altered or omitted without departing from the spirit of this invention as defined by the following claims:—

I claim:

1. A form clamp comprising a flexible tie element, a collar mounted on said element and adapted for adjustment longitudinally thereof, means for locking said collar to said element, and a detachable tool arranged to grip said tie element and being adapted to be fulcrumed on said collar for pulling said element relative to said collar.

2. A form clamp comprising a tie element,

- a collar mounted on said element and adapted for adjustment longitudinally thereof, means for locking said collar to said element, a detachable tool having a slot formed therein for receiving a part of said element projecting through said collar, and means on said tool arranged to grip said projecting part, said tool being adapted to be fulcrumed on said collar for pulling said element relative to said collar. 55
6. A form clamp comprising a tie element, a collar mounted on said element and adapted for adjustment longitudinally thereof, means for locking said collar to said element, a detachable tool having a slot formed therein for receiving a part of said element projecting through said collar, and means coacting with said slot for locking said projecting part to said tool, said tool being adapted to be fulcrumed on said collar for pulling said element relative to said collar. 60
7. A form clamp comprising a collar having a slot extending therethrough, a flexible tie band extending through said slot, a tool arranged to grip said flexible band and being adapted to be fulcrumed on said collar for pulling said band relative to said collar, and means on said collar arranged to grip said flexible band. 65
8. A form clamp comprising a collar having a pair of intersecting slots extending therethrough and disposed at substantially right angles to each other, a flexible tie band extending through one of said slots, a detachable tool arranged to grip said flexible band and being adapted to be fulcrumed on said collar arranged to grip said flexible band. 70
9. A form clamp comprising a collar, a flexible element adapted to embrace the form and having one end secured to said collar, the other end of said element extending through said collar and being adjustable with respect thereto, a detachable tool arranged to grip said other end of said flexible element and being adapted to be fulcrumed on said collar for pulling said other end relative to said collar, and means on said collar arranged to grip said other end. 80
10. A form clamp comprising a collar having a pair of intersecting slots extending therethrough and disposed at substantially right angles to each other, a flexible band adapted to embrace the form and having one end secured to said collar, the other end of said band extending through one of said slots and projecting beyond said collar, a detachable tool arranged to grip the projecting part of said band and being adapted to be fulcrumed on said collar for pulling said other end relative to said collar, and a wedge in the other of said slots for clamping said other end of said band to said collar. 85
11. A form clamp comprising a flexible tie element, a collar mounted on said tie element and adapted for adjustment longitudinally thereof, means for locking said collar to said element, a detachable tool having a pair of intersecting slots of different sizes extending therethrough and disposed at substantially right angles to each other, one of said slots being arranged to receive a part of said element projecting through said collar, and a wedge in the other of said slots for clamping said element relative to said collar. 90
12. A form clamp comprising a flexible tie element, a collar mounted on said tie element and adapted for adjustment longitudinally thereof, means for locking said collar to said element, a detachable tool having a pair of intersecting slots of different sizes extending therethrough and disposed at substantially right angles to each other, one of said slots being arranged to receive a part of said element projecting through said collar, and a wedge in the other of said slots for clamping said element relative to said collar. 95
13. A form clamp comprising a flexible tie element, a collar mounted on said tie element and adapted for adjustment longitudinally thereof, means for locking said collar to said element, a detachable tool having a pair of intersecting slots of different sizes extending therethrough and disposed at substantially right angles to each other, one of said slots being arranged to receive a part of said element projecting through said collar, and a wedge in the other of said slots for clamping said element relative to said collar. 100
14. A form clamp comprising a flexible tie element, a collar mounted on said tie element and adapted for adjustment longitudinally thereof, means for locking said collar to said element, a detachable tool having a pair of intersecting slots of different sizes extending therethrough and disposed at substantially right angles to each other, one of said slots being arranged to receive a part of said element projecting through said collar, and a wedge in the other of said slots for clamping said element relative to said collar. 105

Signed at Chicago this 2 day of Feb. 1923.

GEORGE B. BOSCO.
